UNITED STATES PATENT OFFICE

OSKAR MESSTER, OF BERLIN, GERMANY

METHOD OF AND DEVICE FOR SHOWING CINEMATOGRAPHIC PICTURES

Application filed April 16, 1928, Serial No. 270,484, and in Germany December 7, 1927.

This invention relates to the showing of cinematographic pictures, and its object is on the one side to warrant a proper accommodation of the speed of the successive pictures with respect to the scene they show, that is to say, to prevent a too quick, as well as a too slow succession of the pictures during the entire showing, and on the other side to finish the showing within the time predetermined for the respective play or performance.

This is attained in a particularly simple manner, viz. merely by regulating the running of the cinematographic apparatus in continual correspondence with the running of the seconds-hand of a clock. This can be effected, for instance, by turning a hand by the driving gear of the cinematographic apparatus, the speed of this latter being then regulated according to the speed of that hand in such a manner that this hand and said seconds-hand (which may indicate tenths of seconds) always lie one over the other. If the hand driven by the cinematographic apparatus is leading, the speed of this apparatus must be retarded, whereas when the seconds-hand is leading the speed of said apparatus must be accelerated, in both cases in a degree that the two hands again cover one the other.

The invention is illustrated diagrammatically and by way of example on the accompanying drawing on which Figure 1 is a front view of a device for practicing the method in question; Figure 2 is a side-view of this device, partly in section; Figure 1a shows some details of Fig. 1; Figures 3 and 4 are diagrammatic illustrations elucidating the manner of operation of the device; Figure 5 is a side-view of some parts pertaining to a modification; Figures 6 and 7 are also diagrammatic views pertaining to this modification; Figure 8 is a diagrammatic view showing the device connected with the driving gear of a motion picture machine.

Referring to Figs. 1 and 2, *a* denotes a shaft which is connected to the driving shaft of the cinematographic apparatus *B* by a flexible shaft *a'* or the like so that the shaft *a* rotates at the same speed as the shaft of

the cinematographic apparatus; the speed of this shaft corresponds to the speed of the member (for instance a Maltese cross) by which the film to be shown is moved forward. A pinion *b* secured to the end of the shaft *a* meshes with a cog-wheel *b'* affixed to a shaft *c* bearing also a smaller cog-wheel *b''* meshing with a cog-wheel *b'''* secured to the shaft of a worm *d* meshing in turn with a worm-wheel *e* supported upon an axle *f*. This axle carries also a collar *g* which contacts with the worm-wheel and is rotated along with it, and from said collar projects an arm *g'*, which is formed similar to a **U**, and the front part of which forms a hand *h*. Near said collar the arm *g'* is provided with a pin *g''* co-operating with a star-wheel *i* in a manner hereinafter fully described. The wheel *i* is carried by an arm *i'* affixed to the shaft *f*. The short shaft of the star-wheel *i* is supported in the end of the arm *i'* and carries on the other side of this arm a pinion *j* meshing with a large cog-wheel *k* supported loosely upon the axle *f*. A **U**-shaped arm *k'* is attached to the rim of the wheel *k* and the free end of this arm forms a hand *m* intended to co-operate with the hand *h* in the manner already indicated in the introductory part of this specification.

At the free end of the shaft *f* is a holder *n* for a pocket watch *A* of the type known as stop watch. The ends of the hands *h* and *m* lie just in front of the ends of the hands of said watch, and the arrangement is such that the hand *h* co-operates with the quickly rotating seconds-hand *h'* (Figs. 3 and 4) of the watch and the hand *m* co-operates with the slowly rotating minute-hand *m'* (Figs. 3 and 4) of the same. As the watch *A* is a stop-watch, as already mentioned, it is possible to stop the seconds-hand by depressing the knob *o* of the watch, and to re-start it by another pressure, and so on, as known. It is suited to the purpose to make use of a watch, the seconds-hand of which makes one complete revolution in 30 seconds, as is the case with the watch to which the Figs. 3 and 4 pertain, but it is also possible to employ a stop-watch in which the seconds-hand performs one complete revolution in 20 seconds,

as is the case with the watch to which the Figs. 5-7 pertain.

The manner of operation of the device is as follows:

- 5 The hand m is adjusted to the position corresponding to the point of time at which the performance commences, the seconds-hand h' is adjusted to its initial position, as in Fig. 1, and the hand h is so adjusted as to cover 10 the hand m . Now the hand h' is released by a pressure upon the knob o and commences, therefore, to move. In that moment in which the tip of the hand h' arrives at the tip of the hand h (or a little earlier because of the 15 slight retardation caused by the starting of the watch), the motor of the cinematographic apparatus is switched on, in consequence whereof the shaft a is rotated. The cinematographic apparatus runs as long with the 20 proper speed as the hands h and h' , or their tips respectively, lie opposite one another, that is to say, the speed of the apparatus corresponds to the speed of the watch. This is shown in Fig. 3. If, however, the hand h 25 is leading with respect to the hand h' , as in Fig. 4, the cinematographic apparatus must be retarded until the two hands in question, or their tips respectively, lie again opposite one another. If, however, the hand h' 30 should be leading, the running of the cinematographic apparatus must be accelerated.

It may occur that the service or performance is disturbed, for instance by the film 35 tearing, and it is, therefore, necessary to make provisions permitting the operator to make up for the lost time. For this purpose the hand m is provided which is moved in steps by means of the pin g^2 , the star-wheel i , and 40 the gearing j , k , in other words, the hand m is turned for a certain angle when the hand h performs one complete revolution, that angle being, of course, in a certain ratio to the subdivision of the seconds-part of the 45 watch dial. In the example shown in Figs. 1-4, that part is subdivided into 30 seconds, and the hand h' makes, therefore, one complete revolution in 30 seconds. When the hand h' has made two revolutions, which 50 together correspond to one minute, also the hand m will have been turned as much as corresponds to one minute. Supposing, now, an interruption of the service or performance should occur, the three hands of the watch 55 (including the hour-hand) will proceed in their course, whereas the hands h and m stop. Now the hand m is leading with respect to the hand m' , and the difference between these hands permits the operator to see distinctly 60 how much he must accelerate the running of the cinematographic apparatus in order to make up for the lost time, the acceleration being effected until the hand m lies again opposite the hand m' , from which point of 65 time the speed of the cinematographic appa-

ratus is so diminished that the tip of the hand m remains opposite the tip of the hand m' . When then also the tip of the hand h has arrived opposite the tip of the hand h' the apparatus runs again with normal speed, that is to say, the succession of the pictures proceeds normally in accordance with the time predetermined for the entire performance.

In order to place the operator in the position to predetermine any desired point of time as commencement of the performance, the hands h and m can be turned manually at will. Concerning the hand h it has already been mentioned, that the collar g to which the arm g' (the end of which forms the hand h) is affixed is turned by friction by means of the worm-wheel e . This does not prevent the collar from being turned manually at liberty upon the axle f without impairing its rotation by said worm-wheel in the intended manner. The same is true of the cog-wheel k which can be turned manually at liberty, provided, the pin g^2 be not located at that time between two teeth of the 90 star-wheel i .

In the modification shown in Figs. 5-7 the watch A has merely a seconds-hand h' , and in front of this watch is arranged a rotatory glass disk p having a hand h merely marked upon it, for instance in the form of a short radial black line. The glass disc h is fitted in a ring e' provided on its circumference with worm-teeth which mesh with a worm d whereby the disk p can be rotated. It is secured in its centre to a short axle supported by a bearing r . The worm d is connected with the driving gear of the cinematographic apparatus by an intermediate gearing, preferably such as has been described with reference to Figs. 1 and 2 (b , b' , b^2 , b^3). When the mark h is located just in front of the hand h' , the cinematographic apparatus runs with the proper speed, whereas if the mark is leading the cinematographic apparatus runs too quickly and must, therefore, be retarded.

In order to be in the position to make up for lost time also with this modification, there is provided, besides the watch A, another watch A' arranged, in the example shown, below the watch A. This watch A' may have a wheel-work of its own or may be driven by a wheel-work common to both watches, and its hands are the usual ones, viz. a minute-hand and an hour-hand. A rotatory glass-disk like p is provided also in front of the watch A', and is also rotated by such means as provided for the glass-disk of the watch A. m on the watch A' denotes the seconds-hand of the same, and m' denotes the hand-like mark upon the adjacent glass-disk (not shown). Also this disk is turned positively by the driving gear of the cinematographic apparatus, and it is, therefore, also with this modification possible to adjust the speed of 130

that apparatus according to which of the hands is leading.

The method dealt with in the preceding paragraphs can be used also in connection with several cinematographic apparatus to be actuated all at a time and in correspondence with acoustic reproductions (music, singing, lecture or the like explaining the images) by telephone or radio. The running of the individual cinematographic apparatus, 10 as well as the running of the cinematographic apparatus put up in the transmitting room, or of an acoustic reproduction apparatus, for instance for a phonogram written upon 15 a film, is then regulated with the aid of suitably running watches which have been adjusted prior to the commencement of the performance in correspondence with the watch or clock pertaining to the cinematographic apparatus put up in the transmitting room. 20

I claim:

A device for regulating the showing of cinematographic pictures, comprising, in combination with the cinematographic apparatus, a shaft rotated by the driving gear of the same, transmission wheels driven by said shaft, a worm wheel driven by said wheels, an axle upon which said worm wheel is loosely rotatable, a watch attached to the 25 free end of said axle and having a minute hand and a seconds-hand, a collar also supported upon said shaft and turned by the worm-wheel, an arm affixed to said collar and forming at its free end a hand adapted 30 to co-operate with the seconds-hand of said watch, a cog-wheel also supported on the said axle, an arm secured to this wheel and forming at its free end a hand adapted to co-operate with the minute hand of the said 35 watch, and means for turning said latter 40 wheel in steps, every step taking place at a complete revolution of the said collar with its arm, substantially as set forth.

In testimony whereof I affix my signature.

OSKAR MESSTER.
